UNITED STATES PATENT OFFICE.

FRANZ ZACHHUBER, OF AMBERG, GERMANY.

DEVICE FOR THE MANUFACTURE OF METALLIC PROTECTING TUBES.

Application filed February 6, 1923. Serial No. 617,394.

To all whom it may concern:

Be it known that I, FRANZ ZACHHUBER, a citizen of the German Republic, and a resident of Amberg, Bavaria, Germany, have invented certain new and useful Improvements in Devices for the Manufacture of Metallic Protecting Tubes, of which the following is a specification.

This invention relates in general to a device for the manufacture of metallic protecting tubes for use in connection with the laying of electric wires, and in particular to a tube drawing tool with the aid of which, while the wires are being laid, a strip of sheet metal is transformed into a tube surrounding or enclosing and protecting the laid wire or wires. In particular this invention relates to improvements in devices of this kind which are known per se, but are possessed of certain drawbacks which are overcome by this invention. First of all an unobjectionable tube is produced by a specially suited configuration of the mouth-piece and by a specially provided tubular guide at the delivery end of that device. This tube is distinguished by its overlapped seam and leaves the tubular mouth piece as a straight tube which neither unwinds, nor has a tendency to turn around its longitudinal axis similarly to the threads of a screw. Besides, the comparatively great resistance experienced with tube drawing devices with stationary preliminary drawing cheeks when drawing or shaping the sheet metal tube, and to be overcome by an increased expenditure of power, is obviated by using as preliminary drawing device a rotary pair of rollers, of which one is practically of spherical shape and which both serve also for the preliminary rounding of the sheet-metal strip. These rollers, although being subject to pressure and doing also the preliminary drawing work, unroll easily along the sheet-metal strip pulled through between them and insure, besides, a good guidance therefor along the middle of its length, thereby preventing lateral displacement and making the strip enter the mouth-piece always in right position.

Generally one pair of rollers will do, but, if desired, or necessary in particular cases, two or even more may be arranged in succession.

It is suited to the purpose to provide the spherical roller with a circumferential groove which receives, or through which

pass, the wire or wires to be enclosed in the protecting tube, the wire or wires moving along together with the protecting tube formed and being always in right position 60 relatively thereto, or to the strip respectively, which may bend around the wire or wires without any trouble. The groove mentioned is particularly advantageous if several wires are to be enclosed in the metal 65 strip tube, as the groove holds the wires together and insures their right entrance into the mouth piece together with the strip so that the strip which is bent preliminarily by the members effecting the preliminary 70 drawing is transformed into a tube without any trouble and in accurate position relatively to the wires which are enclosed thereby. The wires are thus, where a circumferential groove, as mentioned, is provided, inserted immediately at the rollers, whereas, if there is no such groove, the wires can be inserted only behind the rollers or between them and the drawing mouth piece.

My invention is illustrated, by way of example, in the accompanying drawings, in which Fig. 1 is a plan of the device; Fig. 2 is a longitudinal section therethrough; Fig. 3 is a side view thereof; Fig. 4 is a separate view solely of the drawing mouth piece, in longitudinal section; Fig. 5 is a rear or inner or edge view of said mouth piece; Fig. 6 is a transverse section through the mouth piece, drawn on a larger scale; Fig. 7 is a separate view of the pair of rollers, the transverse section of the casing forming lateral members lying in line A—B of Fig. 3. Fig. 8 is a transverse section in line C—D of Fig. 3 and shows the guide means for the sheet metal strip. Fig. 9 is an illustration similar to Figs. 4 and 5 and shows a modification of the drawing mouth piece; Figs. 10, 11 and 12 are transverse sections through this modified mouth piece in the lines E—F, G—H and J—K of Fig. 9, drawn on a scale 100 like that of Fig. 6. Fig. 13 is an illustration similar to Fig. 7 showing a modification of the spherical roller; Figs. 14 and 15 are similar illustrations showing also modifications of the rollers.

The device or tool consists of a frame 1 composed of sheet-metal members and provided at its rear end with a handle 2. The sheet-metal strip intended to be transformed into a tube is coiled, as shown at 7, Figs. 1 110 and 2, this coil being supported by a pin or spindle that is removable in order to receive

another coil if the preceding one has been worked up. The strip 7 runs through two parallel guide members 3, Figs. 1, 2 and 8, which are guided by a transverse pin and through which passes a screw-threaded spindle having a right-handed and a left-handed thread by which the distance between the guide members may be varied, i. e. adjusted to the breadth of the metal strip 7.

10 There then follows, in the direction to the mouthpiece, the two rollers 4 and 6, Figs. 1 to 3 and 7, which are carried by pins supported in the frame 1, and of which the roller 4 is practically spherical, whereas the 15 roller 6 has a circumferential shape corresponding to the shape of the roller 4. This roller is held in place not solely by the lateral frame members, but also and chiefly by two lateral members 12 which are longitudinally slotted and are arranged obliquely with respect to the frame and are each under the pull of a coiled spring 12^a secured at one end to the respective member 12 and at the other end to a pin 12^b projecting forth from 20 the respective side of the frame through the slot 12^c. The laterally projecting parts of the members 12 form bearings for the axle 4^a of the spherical roller 4, and this axle is pulled by the springs 12^a into hook-like projections 1^a of the lateral frame members 1, as visible especially in Fig. 3. It is therefore possible to draw the axle 4^a with the roller 4 out of said hooks 1^a and to swing the parts 4 and 4^a around the pins 12^b so as to 25 move the roller 4 out of and away from the roller 6.

8, Figs. 1 and 2, is a lubricating cushion for the metal strip 7 that passes along over it on its way from the pair of rollers to the 30 mouth-piece, as illustrated in Fig. 2.

The metal strip 7 passes from the coil 7 through between the guide members 3 to the rollers 4 and 6 between which it is preliminarily bent. At the same time the wires 13 are introduced into the groove 5 of the spherical roller 4, as well as into the channel-shaped metal strip 7 (Fig. 2), the latter glides then over the lubricating cushion 8 and gets into the drawing mouth piece 9 to 35 11, in which the preliminarily bent or rounded strip is turned into a tube, the rims of which overlap one another, as shown in Figs. 5 and 6.

As the groove 5 of the roller 4 forms a 40 guide for the wires while these are introduced into the preliminarily bent metal strip, holding them in proper position relatively to each other, as well as to the bent strip, the work of enclosing the wires in the protective tube is done in most satisfactory manner, requiring no particular attention of the workman.

45 Anyhow, it is not indispensably requisite to make use of a spherical roller having a groove like 5, Fig. 7, but it is possible to

use a complete spherical roller, such as 4^b, Fig. 13, the wires being in this case placed into the metal strip only after it has made its way through between the rollers and has been preliminarily bent to form a channel, as 50 described. The roller 6^b, Fig. 13, is practically such a one as the roller 6 of Fig. 7.

The roller pairs 4^c—6^c, Fig. 14, and 4^d—6^d, Fig. 15, are not two modifications, but are intended to be used simultaneously, that is 55 to say, they form parts of one device in which they act one after the other, the sheet-metal strip being first acted on by the rollers 4^c and 6^c and then by the rollers 4^d and 6^d. It is a matter of course that in the case of 60 two pairs of rollers the device is correspondingly longer. Each pair is arranged and supported exactly in the manner illustrated in Figs. 1 and 3, especially as regards the slotted members 12, the springs 12^a, and the 65 hooks 1^a. Effecting the preliminary bending in two stages facilitates this procedure, also as regards the closing of the channel to form the protective tube. The co-operation of the two pairs of rollers with the drawing 70 mouth piece is just the same as in the first case. The metal channel arrives at the mouth-piece in position to be properly closed during its passage therethrough, the rims 75 overlapping one another.

The drawing mouth piece 9, Figs. 1 to 4, is exchangeable; it is held in place by a kind of clasp 10 attached to the frame of the tool, and has a longitudinal guide groove 14 extending either through the entire 80 length of the mouth piece or disappearing finally as in the modification illustrated in Figs. 9 to 12 in which a comparison of Figs. 10 and 12 shows that the orifice of the drawing mouth-piece (plane J—K, Figs. 9 and 12) is perfectly circular, the overlapping 85 rim of the tubular strip forming part of the circle, in contradistinction to Figs. 5 and 6 where the overlapping rim lies outside of the circle.

The end of the tool is formed by a piece of tube 11 which is arranged at a certain obtuse angle with respect to the longitudinal axis of the frame of the device or tool.

The guide groove 14 guides only one of 90 the rims or edges of the metal channel 7, the other rim or edge being free to move round within the mouth piece so as to approach the guided rim or edge and overlapping it, as shown in Figs. 5 and 6, as 95 well as in Figures 10 to 12. Owing to the metal channel being thus guided, it is completely prevented from distortion, the overlapping appearing as a straight line. If 100 the guide groove 14 terminates before the orifice of the drawing mouth piece, as in Figs. 9 and 12, the overlapping rims are 105 pressed against one another, that is to say, the outer rim is pressed against the inner, the outer diameter of the finished tube being 110 115 120 125 130

then exactly equal to the diameter of the orifice of the mouth piece (Fig. 12).

In view of the fact that a certain inner tension arises in the metal strip, or metal channel, while being acted on by the shape-giving members of the device, the finished tube would slightly bend or curve when leaving the device, necessitating a subsequent straightening. To obviate this, the angularly arranged outlet tube 11 is provided, the effect of which is, as practical experience has shown, that the finished tube remains perfectly straight, there being no tendency to bend or curve after it has been forced through the obtuse angle existing between that outlet tube and the drawing mouth piece.

The frictional resistance arising during the passage of the metal strip through the device is considerably reduced by the preliminary bending members being rollers, such as 4 and 6, as well as 4^b and 6^b, 4^c and 6^c, and 4^d to 6^d, there being rolling friction instead of gliding friction; and the resistance is still more reduced if the tube is closed already in the drawing mouth piece, as in Figs. 9 to 12, instead of only in the outlet tube 11, as in Figs. 1 to 4.

I claim:—

1. A tool for transforming sheet-metal strips into protecting tubes for electric wires while laying the latter, comprising, in combination, a practically spherical roller; a correspondingly shaped counterpart therefor; means for supporting a coiled sheet-metal band located in front of said roller and its counterpart; and a drawing mouth piece located behind the said roller and its counterpart as regards the direction of motion of the sheet-metal band during its passage through the device, and having a guide-groove for one of the rims of the metal

band, said groove having a slight lateral turn on its way from its one end to its other end.

2. A tool for transforming sheet-metal strips into protecting tubes for electric wires while laying the latter, comprising, in combination, a practically spherical roller; a correspondingly shaped counterpart therefor; means for supporting a coiled sheet-metal band located in front of said roller and its counterpart; and a drawing mouth-piece located behind the said roller and its counterpart, as regards the direction of motion of the sheet-metal band during its passage through the device and having a guide groove for one of the rims of the metal band, said groove having a slight lateral turn on its way from its one end to its other end but ending somewhat before the orifice of said mouth-piece so as to let this orifice be circular, for the purpose set forth.

3. A tool for transforming sheet-metal strips into protecting tubes for electric wires while laying the latter, comprising, in combination, a practically spherical roller; a correspondingly shaped counterpart therefor; means for supporting a coiled sheet-metal band located in front of said roller and its counterpart; a drawing mouth-piece located behind the said roller and its counterpart as regards the direction of motion of the sheet-metal band; and an outlet tube attached to the end of said mouth-piece and being located at an obtuse angle with respect thereto, substantially and for the purposes set forth.

In testimony whereof I affix my signature in presence of two witnesses.
